UNITED STATES PATENT OFFICE

NATHAN A. HEACOCK, OF SULLIVAN, ILLINOIS.

IRRIGATING SYSTEM.

1,130,282.

Specification of Letters Patent. Patented Mar. 2, 1915.

Application filed June 3, 1913. Serial No. 771,568.

To all whom it may concern:

Be it known that I, NATHAN A. HEACOCK, a citizen of the United States, residing at Sullivan, in the county of Moultrie and State of Illinois, have invented certain new and useful Improvements in Irrigating Systems, of which the following is a specification.

My invention relates to irrigating systems and particularly to that class of irrigating system wherein supply pipes are used to discharge water upon a field and a drain pipe used for carrying off the water after it has done its work.

The primary object of my invention is to provide an irrigating system particularly applicable to rice growing or the raising of like crops in which it is necessary to provide means for controlling the period during which water may be kept upon the land and controlling the depth thereof.

A further object of my invention is to provide very simple means of the character stated whereby water may be let onto and drawn off the land at will and whereby the height of the water upon the land may be controlled.

A further object is to provide means whereby relatively small sections of a field may be flooded or drained as desired.

Still another object is to provide means whereby the water may be withdrawn from the pipes of the irrigating system. And another object is to provide means whereby the inlet of sediment into the drain pipe may be prevented and this sediment removed from time to time as convenient.

Still a further object is to so arrange the pipes of the system that water may be uniformly distributed to all parts of each small area or section of the field to which the irrigating system is to be applied.

Other objects will appear in the course of the following description.

For a full understanding of the invention, reference is to be had to the following description and accompanying drawings, in which:

Figure 1 is a plan view of an irrigating system constructed in accordance with my invention; Fig. 2 is a plan view of another arrangement of this irrigating system; Fig. 3 is a perspective view of a portion of one of the supply pipes and its discharge outlets

partly broken away; Fig. 4 is a fragmentary section of the discharge pipe; Fig. 5 is a perspective view of the drain pipe and inlet thereto; Fig. 6 is a sectional view of the same; and Fig. 7 is a transverse section of the arrangement shown in Fig. 2.

Referring to the drawings, A designates a portion of a field inclined from B toward C so that the natural drainage of the land will be from B toward C. This field is laid off into relatively small sections a by means of dikes 2 which are disposed in approximately parallel relation and which extend in the direction of the incline of the land.

In the arrangement shown in Fig. 1 there is a distributing pipe 3 disposed across the upper end of the field and supported in any suitable manner. This pipe is connected by means of branch 4 to a reservoir 5 of any suitable capacity, this reservoir being in turn connected to any suitable source of water. This source in the drawing is shown as a well designated 5a. The pipe 3 may extend along the upper edge of a field of any desired size and the pipe may be of any desired length. The pipe is preferably made of drain tile sections, the sections being impervious to water, however, but being laid below ground as illustrated in Fig. 3. At intervals the sections of the pipe 3 are provided with laterally extending outlets or branches 6 which communicate each with a vertical pipe 7. This pipe 7 extends below the level of the pipe 3 and is closed at its lower end as at 8. The pipe 7 extends above the ground and is then bent over as at 9, so as to discharge downward onto the ground from any suitable height. The discharge end 9 of the pipe is provided with any suitable valve whereby the discharge through the pipe may be controlled. The valve is designated 10 and is illustrated as in the form of an inverted cone disposed below the discharge end of the bend and having an upwardly extending handle or spindle 13. This valve is so constructed as to close or partly close the pipe, depending on the flow of water required.

The portion 11 of the pipe 7 forms a sediment collecting trap, and in this trap is disposed a sediment collector consisting of a vessel 14 having a handle 14a. The pipe 7 is made in two sections so that the upper section 7a may be removed to permit the re-

moval of the catch basin or vessel 14, and for a purpose to be later stated. It will of course be understood that there are as many of these pipes 7 as there are small sections ⁵ *a* of the field A. At the lower ends of the sections *a* into which the field A is divided, there is disposed a longitudinally extending drain pipe 15. This drain pipe is shown as extending parallel to the pipe 3 but is not necessarily so disposed. This drain pipe discharges at one end into a receiving reservoir 16 which in turn is connected by means of the pipe 17 to a receiving reservoir 18. The water received in the reservoir 18 may be pumped or otherwise carried back into the reservoir 5 or otherwise removed. The reservoir 16 may also be provided with a discharge outlet 19.

The pipe 15 is connected at intervals to a plurality of upwardly extending branch pipes 20 as illustrated in Fig. 6, these vertical pipes 20 extending below the pipe 15 so as to form a trap 21 at the lower end of each pipe for the purpose of catching sediment. Within each pipe 20 is disposed the catch basin or vessel 22 provided with the handle 23. The upper end of the pipe 20 is provided at its outlet end with a protector comprising a cylindrical screen 26 inserted in the upper end of the pipe 20. The upper end of this screen 26 has an imperforate head 27. Mounted on and resting upon this head 27 is an outer cylindrical screen 28 having an imperforate head 29. This screen 28 surrounds the screen 26 in spaced relation thereto. The purpose of these screens is to protect the intake of the pipes 20 from trash, leaves, coarse sediment or like material which would tend to obstruct the pipes. Co-acting with the screens 28 and 26 is a hollow drum or cover 30 which is imperforate and is adapted to be placed over the cylindrical screen 28. The purpose of this drum is to prevent water from passing through the screened intakes until the field is to be drained. This drum is to be raised and lowered to control the water to suit the exigencies of any particular time. There are of course to be as many pipes 20 leading into the main drainage pipe 15 as there are sections *a* of the field to be irrigated. The flow of water from the reservoir 5 is to be controlled by means of a valve 31 so that the water may be entirely cut off from the pipe 3 and therefore from the land, or may be admitted to the pipe at will.

The operation of my invention will be obvious from what has gone before. In certain seasons of the year it is most desirable to have the land entirely dry, and in this case, of course, either the reservoir 5 may be drained entirely or the valve 31 closed. In this case the natural drainage from the land will be received in the reservoir 16, and carried from the sump or reservoir 16 to the

reservoir 18 or let out through the outlet pipe 19. The water after it has passed from drain pipe 15 to reservoir 16 in no case is returned to reservoir 18 unless wanted to be used on the field again for irrigation.

When it is desired to flood the land, the valve 31 is opened permitting the water to flow from the reservoir 5 into the pipe 3 and thence to any one of the sections *a*, depending upon the position of the several valves 10. If the valves 10 of all of the pipes 7 are opened it is obvious that all of the sections will be flooded and that by controlling the respective valve the water let onto any particular section *a* may be controlled. If the hoods or covers 30 are kept in place closing the outlets through the pipes 20, it is obvious that the water will gradually rise between the dikes 2, that the land will be flooded and that this flooded condition of the sections may be kept as long as desired and that the height of the water may be regulated to any desired depth. It is also obvious that the height of the water may be increased at any time or decreased at any time and that thus the amount of water upon the land may be at all times accurately controlled.

When it is desired to drain the land it is only necessary to lift one or more of the covers 30, whereupon one or more of the sections *a* will be drained. A constant flow of water may be kept over the land, or it may be intermittently flooded. In other words, the land may be placed in the best possible condition for cultivating those crops requiring the keeping of water upon the land through certain periods of time.

The construction shown in Fig. 2 has the same principle as that previously described. In this adantation of my system as in that shown in Fig. 1 the field A is divided off into relatively small sections *a* by the transverse dikes 2, these dikes running parallel to the inclination of the land, this inclination being from the part B to the part C. Extending downward across one end of the field is a main supply pipe 33 which is connected at intervals to longitudinally extending pipes or secondary supply pipes 34 which extend parallel along the field. As illustrated there are three of these secondary supply pipes. Each of the secondary supply pipes is provided at intervals with the upwardly extending discharge pipes 7, such as are illustrated in Fig. 3 and heretofore described. All of the secondary pipes 34 are connected to the drain pipe 40 which extends transversely of the pipes 34 and discharges into reservoir or sump 16. Valves ¹²⁵ 40^a are disposed at the intersection of the secondary pipes 34 with the pipe 40. The reservoir or sump 16 is connected by means of the return pipe 17 to the receiving reservoir 18, which is connected to the main reser-

voir 5. Disposed at the lowest portion of the field and extending approximately parallel with the pipes 34 is the drain pipe 15, discharging into reservoir 16. This drain pipe is provided at a plurality of points with the inlet pipes 20, which extend up to the surface of the ground, as previously described, and are provided with screens 26 and 28, previously described and adapted to be closed by means of the hoods or covers 30. The flow of water through the main pipe 33 is controlled by means of the valve 31.

It may here be noted that in both cases illustrated the mouths of the pipes 7 carried by any one supply pipe are to be so located with relation to the surface of the ground immediately beneath them that all of said mouths will be at the same distance from the surface of the ground. In order to prevent the discharge of water from the pipes 7 from tearing up the ground, I may provide beneath the outlet of each of the pipes 7 a receiving basin designated 50 having laterally disposed pipes 51. This receiving basin 50 and the pipes 51 lie upon the surface of the land, and water from the discharge pipe 7 is discharged into the basin which is open at its upper end while the pipes 51 carry the water to different portions of the same sections, or these pipes may be used to carry water to one or more adjacent sections, that is, the sections being considered to be those portions of the land divided by dikes. This would dispense with a discharge pipe 7 for each section. In Fig. 1 I show half of the sections as being provided with the receiving basins 50 and laterally disposed pipes 51, the other sections not being provided with these basins and pipes.

40 The discharge pipes 7 as shown in Figs. 2 and 7 are of the same construction as the discharge pipes shown in Fig. 4 and made in two portions, the upper portion being removable, the junction of the sections 7 and 7^a being at a level with the ground. Under these circumstances the secondary pipes 34 may act as drainage pipes so as to thoroughly drain the land of water. Normally when the pipes 34 are acting as discharge pipes, the valves 40^a are closed, but when it is desired to drain the land thoroughly, the valves 40^a are opened and the discharge sections 7^a are removed and screen intakes such as shown in Figs. 5 and 6 are placed within 55 the upper portions of the vertical pipes 7, thus making a complete system of drainage.

60 The operation of the form of the invention shown in Fig. 2 is the same as that previously described for that shown in Fig. 1. The only differences are that water will flow into the secondary pipes and be more evenly distributed over the sections of the field, and that these secondary pipes 34 may be used as drainage pipes as above described. As 65 in the former case, the flow of water onto

the field, the flow of water from the field and the depth of water kept upon the field may at all times be regulated by adjusting the valves 10, 31 and the hoods 30.

I have found that my improved system 70 of irrigating is particularly valuable in rice planting, but it may be used for all crops wherein it is necessary to retain water upon the land for various periods.

I do not wish to be limited to the use of 75 any particular material for the various pipes of the system, but I have found ordinary drain tile entirely adapted for the purpose.

Having thus described the invention, 80 what I claim is:

1. An irrigating system of the character described including a supply pipe and a drainage pipe, said pipes extending approximately parallel to each other, the land 85 between the supply pipes and the drainage pipes being divided into relatively small sections by means of transverse dikes, a plurality of upwardly extending outlet pipes connected at intervals to the supply pipe, 90 each of said outlet pipes being formed in two sections, one of said sections terminating approximately level with the ground, the upper section being removable from the first-named section, and a screening member 95 adapted to be disposed upon the lower section of each of said pipes.

2. An irrigating system of the character described including a supply pipe and a drainage pipe extending approximately parallel to each other, the supply pipe being disposed at a higher level than the drainage pipe, a reservoir with which the supply pipe is connected, means for controlling the passage of water from the reservoir to the supply pipe, a plurality of vertical pipes connected to the supply pipe, each of said vertical pipes having a downwardly extending discharge end, valves for controlling the discharge from the respective discharge ends, upwardly extending inlet pipes connected at intervals to the drainage pipe and opening at the surface of the field, screened inlet members carried upon said last named pipes, removable hoods for controlling the passage of water through said drainage inlet pipes, a receiving reservoir into which the drainage pipe empties, a pipe leading from the receiving reservoir, 110 a reservoir into which said pipe discharges, 115 and a drainage outlet from the receiving reservoir.

3. An irrigating system for fields divided into relatively small sections by transverse dikes, said dikes extending from the upper 125 portion of the field to the lower, comprising a supply reservoir, a main delivery pipe leading from said reservoir in the direction of the inclination of the land, secondary pipes leading from said main pipe and ex- 130

- tending transversely of the inclination of the land and of said dikes, discharge outlets from these secondary pipes discharging onto the surface of the land, valves for controlling said discharge outlets, a drainage pipe extending parallel to the secondary pipes and disposed at the lowest portion of the land and formed with drainage openings between each pair of dikes, means for controlling the inlet of water through said drainage openings, a reservoir into which said drainage pipe empties, a return pipe leading from said reservoir, and a reservoir into which the return pipe empties.
- 15 4. In an irrigating system, a pipe disposed below the surface of the ground, a vertical pipe extending upward therefrom and formed in two sections, the upper section being removable and being extended over to discharge downward upon the surface of the ground, and screened intake members adapted to be disposed in place of the discharge sections of said vertical
- 5 pipe to provide for using the first named pipe as a drainage means.
- 10 5. In an irrigating system, a plurality of parallel supply pipes disposed beneath the surface of the ground, a drainage pipe connected to all of said pipes, valves controlling the discharge from said first named pipe into the drainage pipes, discharge pipes each made in two sections extending upward from the first named pipes at intervals, the upper section being removable at a point approximately level with the surface of the ground, and screened intake members adapted to be disposed in the lower sections of the discharge pipes at the surface of the ground when the upper sections of said discharge pipes are removed.
- 15 In testimony whereof I affix my signature in presence of two witnesses.
